[57]

ABSTRACT

A tear-off table calendar having one page for each day of the year arranged horizontally in the stack and glued together along one cut face of the stack defined by one edge of each page, has printing on at least one other cut face of the stack defined by one or more other edges of the pages, the printing displaying a calendarium which is so laid out that a page (or set of pages) relating to a particular day or week can be turned up without difficulty for the purpose of endorsing it with a note of a future event. The calendar also lends itself to conveniently and rapidly inserting a sheet defining a "book mark" (e.g., for the purpose of providing a conspicuous reminder of a future event) in a place between the pages appropriate to the day or week concerned. The calendar may be of a variety of shapes, including a straight or oblique cube, parallelepipedon or cylinder.

CALENDAR

BACKGROUND OF THE INVENTION

This invention relates to a tear-off table calendar comprising a stack of pages which are arranged one on top of the other, are glued together along one cut face defined by the edges, of the pages, and contain particulars about the various days of a year, such as date, day of the week and month.

Tear-off calendars conventionally have one page for each day of the month, having printed thereon the date, day of the week and month and additionally, if desired, also indicating the week, irrespective of whether they are arranged for use as wall calendars or as table calendars for use on desks or the like. The pages are joined together at the back of the stack by a layer of adhesive.

The printed matter on the individual pages may basically be so arranged that some room is left for brief notes. The space available for this purpose is, however, very limited, by reason of the calendar data, unless the pages are inconveniently large. For the purpose of making a note, the stack has to be scanned until the desired date comes into view.

It is an object of the invention to devise a tear-off table calendar of the kind hereinbefore mentioned, wherein on the one hand the entire surface of a page is available for notes with, moreover, a plurality of pages per day available for the purpose, and which on the other hand, can be used for noting down future events, on a calendar page which is readily accessible without the need to turn the pages over individually.

SUMMARY OF THE INVENTION

In accordance with the invention, a calendar providing these facilities is so arranged that at least one non-glued cut face of the stack has printed on the edges of the pages a calendarium in which the days are juxtaposed in numerical order in lines by weeks or months, a plurality of the said lines being arranged one below the other in downwardly staggered formation. In this context "calendarium" means the days of the year arranged by weeks and/or months.

In principle, a calendarium, defining a year's calendar of the kind, for example, which is conventional in pocket diaries, could be printed on the cut face of the stack; the months could, for example, be arranged one below the other in strip-like lines parallel to the cut edges and the days in columns at right-angles thereto. Whilst in such an arrangement the entire surface of each page would be available for notes, the arrangement of the individual pages by the respective days, weeks and months would be lacking, so that such a calendar would not be suitable for use as a diary for recording future events.

Consequently, in a tear-off calendar according to the invention, the successive days are arranged side by side by weeks or months in a plurality of lines one beneath the other, in numerical order and downwardly inclined. By this means it is possible on the one hand to tear off the pages relating to previous days or the present day for the purpose of making notes, without destroying the calendarium of the remaining days of the year; on the other hand the tear-off table calendar can, by reason of the relationship between the days or weeks and the pages, be used as a diary for recording future events.

2

According to a further feature of the invention, there is associated with each day or each week a succession of a plurality of tear-off pages, these being indicated by a mark printed on the cut edges of the pages, the marks of a line being juxtaposed in stepped configuration. By reason of the fact that for each day a plurality of pages are provided, a larger area than in previously proposed calendars is created in respect of each day for notes. The stepped arrangement of the marks, which with respect to each of a succession of pages are each disposed in the same location on the edges of the pages, enables, for example, the insertion of a chit containing a note of a forthcoming conference, between the pages relating to a particular day, the said pages being identified by the mark apertaining to the day in question; the chit may protrude from the tear-off table calendar, so that the individual turning of pages which is entailed in the case of a conventional diary is eliminated.

If only one mark is allocated for each week, it is of course impossible to distinguish the days of the week from each other in the manner described. Such tear-off table calendars are, however, still of advantage, where certain matters have to be dealt with in a particular week and the particular day is of no importance.

In a simplified version of the invention, the month indications are not associated with the individual days, but arranged in at least one column one beneath the other in fields whose height is that of the line spacing, so that the legibility of the calendarium is improved.

It is also possible, for example, to make the tear-off table calendar merely in the form of a half-year etc. calendar, by merely arranging the days or weeks of half a year in the described manner on at least one cut face.

35 BRIEF DESCRIPTION OF THE DRAWINGS

Various forms of tear-off table calendar embodying the invention will now be described, by way of example only, with reference to the accompanying drawings in which:

FIG. 1 shows a first said form of cubic shape with the calendarium on one cut face only, whose days are arranged by months and indicated by line marks;

FIG. 2 shows a second form of calendar, similar to FIG. 1 but with the calendarium distributed over three cut faces;

FIG. 3 shows a third form of cubic tear-off table calendar, in which merely the weeks are indicated by line marks;

FIG. 4 shows the area A in FIGS. 1 and 2 to an enlarged scale;

FIG. 5 shows a fourth, viz. a cylindrical, form of calendar; and

FIG. 6 shows the area B of FIG. 5 to an enlarged scale.

DESCRIPTION OF THE PREFERRED EMBODIMENTS

In FIG. 1 the pages 1 of equal format are stacked one above the other to form a parallelepipedon and joined at a cut face 2 by their cut edges by means of a layer 3 of glue (shown of exaggerated thickness). A calendarium is printed on the front cut face 4. For each day a succession of, for example, five pages is provided, which is indicated by a mark 5. The length of these marks is determined by the length of the edges of the pages, which is subdivided into a maximum of 31

marks, in the present case bar-shaped line marks and additionally into a field 15 for indicating the months.

The line marks for the first 15 days of the month of January commence in the upper left-hand corner of the cut face 4 and are arranged adjacent each other in a stepped configuration. The field 15 for the month indication is adjacent thereto. The line mark for the sixteenth of January is adjacent this field laterally displaced relative to the line mark for the fifteenth of January in such a way (FIG. 4) that the lower margin of the line mark for the fifteenth of January is at the same height as the upper margin of the line mark for the sixteenth of January. The line mark for the sixteenth of January can also be disposed lower down, so that additional note pages are available between these two days. The line mark for the remaining days of January are appropriately arranged adjacent the line mark for the sixteenth of January.

The line mark for the first of February could, in principle, be joined on that for the thirty-first of January to form a step therewith. This would however lead to an inconvenient format for the calendar. For this reason the line mark for the first of February is arranged beneath the mark for the first of January at that height at which it would continue on from that for the thirty-first of January. The line marks for the remaining days of February are arranged relatively adjacent in the appropriate manner.

In this way two stepped configurations of lines are provided which delimit the line 23 for the month of January. The height of the line is determined by the thickness of the paper of the individual pages and by the number of pages provided for each day. The thickness of the paper is so chosen, that the markings are still clearly visible in the region concerned of the edge of the individual pages.

Two parallel line marks, arranged one above the other, respectively delimit the section 16 available for indicating the date and day, for the individual days.

If the height of the line is adequate, the date and week indication may also contain an abbreviated month indication, in which case the field 15 for the month indication inserted in the line is dispensed with (c.f., FIG. 6).

The lines for the succeeding months of the calendar are also arranged on the cut face 4 in the manner described, the fields for indicating the months, which are arranged one beneath the other, forming a column 17.

For example, in order to make an entry for the 15th January, the succession of pages with the first fourteen lines of the first stepped line are turned up, so that the pages provided for the fifteenth of January can be endorsed. It is also possible to insert a card or the like between the pages, as shown for the fourth of December by a note sheet 6 protruding from the calendar. In this way the tedium of turning of pages individually is avoided and the time taken to gain access to a date for which a note has been made is reduced.

FIG. 2 shows a tear-off table calendar, whose year calendarium extends over three cut faces. The lines are arranged in a manner corresponding to FIG. 1, i.e., the calendarium in FIG. 2 is formed from that in FIG. 1, in that the line marks are made of such a length that each succession of lines commences at the edge 10 of the cut face 7 and terminates at the edge 11 of the cut face 9, fields for the month indication (forming columns 18,

19 and 20) being provided on the cut faces 7, 8 and 9.

FIG. 3 shows a tear-off table calendar with weeks indicated by marks. The marks which are in the form of bar-shaped line marks 5' are also arranged adjacent each other in stepped configuration and are disposed on the three cut faces 12, 13, 14 of a cube, which are not glued. The two line marks for the first and second week are disposed on the cut face 12, the line marks for the third and fourth week on the cut face 13, and the line marks for the fifth and sixth week on the cut face 14. The line marks for the seventh and eighth week are disposed on the cut face 12, the line mark for the seventh week being at the level on the cut face 12 at which it would join on to the line mark for the sixth week on the cut face 14.

The length of the line marks in FIG. 3 corresponds to half the length of an edge of the pages 21, whilst the height of the line marks is determined by the number and thickness of the pages provided per week.

Between any two line marks arranged one above the other the date indication for the different days of the week concerned are arranged in fields 22; beneath these fields the month indication is arranged.

The geometric dimensions of the tear-off table calendar according to the invention are not limited to those of the forms shown in the drawing; the calendar may also define a prismatic stack and may, for example, be of cylindrical configuration, the calendarium being arranged on the curved surface.

In FIG. 5, calendar pages 31 in the form of circular discs form a cylinder 32. Along a narrow strip 33, along which the discs (or the cylinder) may also be flattened, they are held together by a glued binding. The calendarium is printed on the remainder of the envelope surface. The different months extend in the form of a band —leaving out the glue strip 33— defining 12 sectors of a helix around the cylindrical surface.

FIG. 6 shows, again to an enlarged scale, the stepped juxtaposition of the line marks 5 (which in FIG. 5 are shown in a simplified manner as a line). The week indication is arranged above, and the month indication beneath the date indication.

It is also possible to provide the embodiments shown in the drawing in such a way that the inscribed cut face extends obliquely to the base plane of the stack (oblique cube, parallelepipedon or cylinder) so that thereby the width of the lines is increased.

Cut faces which are not used for the calendarium or which are free preferably have publicity material printed thereon. The line marks and date indications are applied in known manner, e.g., by screen printing.

We claim:

1. A combination note pad and calendar, comprising a stack of horizontal coextensive superposed paper sheets having a height at least equal to a major edge dimension of the sheets and formed with a vertical cut surface extending along said major dimension; adhesive means extending along another vertical cut surface of the stack to connect said sheets thereto such that successively uppermost sheets can be successively torn from said stack to expose the next lower sheet and thereby diminish the height of the first mentioned surface; and

calendar indicia for a plurality of months printed on said first mentioned surface and extending substantially over the entire area thereof, said calendar indicia including rows of day numerals representing calendar weeks and vertically and horizontally staggered on said surface whereby successive removal of the sheets will progressively eliminate earlier weeks of a month from the calendar indicia of said first surface.

2. The combination note pad and calendar defined in claim 1 wherein the indicia of the days of each week are horizontally and vertically staggered along said first

surface.

3. The combination note pad and calendar defined in claim 2 wherein said stack has the configuration of a cylinder and said first surface extends over the major part of the circumference of the periphery of the cylinder, said indicia being arranged generally helically on said first surface.

4. The combination note pad and calendar defined in claim 2 wherein said stack has the configuration of a rectangular parallelepiped.
